UNITED STATES PATENT OFFICE

LOUIS N. UDELL, OF BOSTON, MASSACHUSETTS

COIL FOR REFRIGERATING AND OTHER APPARATUS

Application filed March 5, 1928. Serial No. 259,337.

This invention relates to coils designed to afford a zig-zag flow of a fluid medium therethrough. In its chief intended application, the coil of my present invention is designed for service in cooling and refrigerating apparatus, either for the passage of a cooling medium, such as cold water or brine, therethrough, or for the flow of a refrigerating gas, such as ammonia; but it may also be used

10 as a radiator of heat, if desired, by connecting it to a source of steam or hot water.

Coils of this character formed from a single length of pipe bent into zig-zag form are known; but such one-piece coils are expensive

15 to make and impractical except from small diameter pipes of comparatively soft and flexible metal. The object of the present invention is to provide a built-up or assembled coil structure that can readily and cheaply be

20 manufactured from pipes of any desired bore, that shall be rugged, strong and fluid-tight, and that can be easily and quickly adjusted to stop a leak, should a leak develop at any of the joints thereof.

25 An approved physical embodiment of the invention is illustrated in the accompanying drawings, in which—

Fig. 1 is a side elevation of the assembled coil;

30 Fig. 2 is an inner face elevation of one of the hollow headers;

Fig. 3 is a longitudinal section of the tapped header taken on line 3—3 of Fig. 4;

35 Fig. 4 is a longitudinal section of the tapped header taken on line 4—4 of Fig. 3;

Fig. 5 is a longitudinal section of the blank header taken on line 5—5 of Fig. 6;

40 Fig. 6 is a longitudinal section of the blank header taken on line 6—6 of Fig. 5;

Fig. 7 is a sectional detail showing one of the packed joints between the pipes and headers.

Referring to the drawings, 10 designates

45 what I term the tapped header and 11 the blank header. The two headers are hollow cast metal structures and are identical except for a difference in the location of their transverse partitions and the provision of tapped holes 12 and 13 in the lower and upper ends

of the header 10 for the reception of inflow and outflow pipes 14 and 15, respectively.

The inner face or wall of each header is provided with a row of holes 15, and encircling and spaced from each hole is an annular groove 16. The tapped header 10 is, in the instance shown, formed with three spaced thin transverse partitions 17, 18 and 19 (Fig. 4), the end partitions 17 and 19 being centrally enlarged and cored forming hollow bosses 17' and 19' to accommodate a pair of tie rods hereinafter described. The blank header 11 is formed with a pair of thin transverse partitions 20 and 21 that are offset relatively to the three partitions 17, 18 and 19 of the tapped header. Extending across the end compartments of the blank header 11 are hollow integral bosses 22 also designed for the passage of the tie rods.

23 designates each of a group of straight 70 pipe sections that extend between the inner faces of the headers 10 and 11. In assembling, two headers 10 and 11 are placed in opposed relation, and the ends of the pipes 23 are fitted into the annular grooves 16 of the two 75 headers with their ends abutting against gaskets 24 seated in said grooves. Tie rods 25 are then passed through the hollow bosses 17', 19', of header 10 and the hollow bosses 22 of header 11, and nuts 26 on the threaded ends of said tie rods are turned up to tightly clamp the headers on the pipes and force the ends of the latter into leak-proof engagement with the gaskets 24. By reason of the described relative disposition of the partitions of the two headers, it will readily be seen that fluid entering through pipe 14 will flow 85 zig-zag fashion through the headers and pipes and out through the outflow pipe 15; or in the same manner in reverse direction, 90 if the direction of flow be reversed.

The described construction affords a strong, substantial and rugged coil structure that is easily and cheaply made and assembled from header castings and straight pipe sections of uniform length, its leak-proof character being most cheaply and conveniently secured by the use of annular grooves receiving the ends of the pipes and gaskets in said grooves. By reason of the fact that the in-

tegral hollow bosses 17', 19' and 22 extend entirely across the flow passages of the headers, the structure is rendered entirely leak-proof at the tie-rod connections without requiring the use of any packings at said connections, and this construction also reduces the height of a coil of given capacity as compared with a like coil having tie-rods located outside the pipe area of the coil. Should 10 leaks at any time develop at the joints, they are readily cured by simply tightening up the nuts 26 on the tie rods 25.

I claim—

1. A coil of the character described, comprising opposed vertical hollow headers formed with horizontally opposed holes in their respective inner faces, parallel pipes extending between said headers and at their ends registering with said holes, means 15 providing fluid-tight joints between said pipes and headers, integral transverse partitions in said headers dividing the latter into flow chambers connecting the ends of adjacent pipes, said partitions being so located as to 20 cause a zigzag flow of fluid through adjacent pipes in opposite directions, integral hollow bosses extending entirely across the flow passages of the headers, the bosses in one of said headers being formed as integral parts of 25 partitions of said header, and tie-rods extending between said headers and through said hollow bosses; one of said headers being formed with lower and upper lateral openings 30 registering with the lower and upper pipes of the coil for connection of inflow and outflow pipes thereto.

2. A coil of the character described, comprising opposed hollow headers with opposed holes in their respective inner faces, parallel pipes extending between said headers and at their ends registering with said holes, means providing fluid-tight joints between 40 said pipes and headers, integral transverse partitions in said headers dividing the latter into flow chambers connecting the ends of adjacent pipes, said partitions being so located as to cause a zig-zag flow of fluid through adjacent adjacent pipes in opposite directions, integral hollow bosses extending entirely across the flow passages of the headers, and tie rods extending between said headers and through said hollow bosses, and said 45 headers being provided with openings for connection of inflow and outflow pipes respectively.

LOUIS N. UDELL.
